UNITED STATES PATENT OFFICE

2,286,145

ROOFING

John Logan, Jr., Chicago, Ill., assignor to The Logan-Long Company, Chicago, Ill., a corporation of Ohio

Application April 17, 1937, Serial No. 137,507

4 Claims. (Cl. 117—25)

My invention relates to roofing, and more particularly to an improvement in the type of roofing used to build up a roof by laying individual overlapping pieces or shingles, or by laying long strips running substantially the length of the roof, as distinguished from roof coverings built or fabricated in place on the supporting roof structure. It includes among its objects and advantages an increase in durability under exposure to weather, and a simultaneous increase in thermal insulating value, accompanied by a decrease in cost of manufacture.

In the accompanying drawings:

Figures 1A and 1B are a diagrammatic side elevation indicating the process of manufacture of roofing according to the invention;

Figure 2 is a transverse section of the finished strip;

Figure 3 is a section as on line X—X of Figure 2, diagrammatically indicating a product according to the prior art;

Figure 4 is a similar section indicating a product according to the invention;

Figure 5 is a similar section indicating a modified product according to the invention;

Figure 6 is a diagrammatic side elevation of an alternative method for the use of extremely fine mica flakes;

Figure 7 is a section as on line 7—7 of Figure 6;

Figure 8 is a diagrammatic side elevation of another form of equipment for taking effective advantage of the insulating properties of the mica with extremely small flakes; and

Figure 9 is a fragmentary section as on line 9—9 of Figure 8.

In the embodiment of the invention selected for illustration, the strip 10 is withdrawn from the roll 12 and passed through a saturating tank 14 and a looper 16. It then passes through a first applicator 18, and a second applicator 20. Thereafter it passes under a hopper 22 where it receives grits 24 over part or all of its upper surface. The roller 26 presses the grits into the surface of the strip and turns the strip the other side up. A hopper 28 is employed to catch excess grits falling off the roller 26, and another hopper 30 catches similar grits falling from the surface of the strip itself. The inverted reach of the strip receives a very thin coating 32 of fine mica. The strip then passes over a roll 34 which turns it right side up again and through a looper 36 to any suitable cutting mechanism.

The applicators 18 and 20 may be generally

according to the applicators disclosed in the co-pending application of Meinrad C. Bothe and Frank X. Pfohl, Serial Number 48,800, filed November 8, 1935, now Patent No. 2,193,472, granted March 12, 1940.

Referring first to the embodiment of Figure 5, the strip 10 receives from the first applicator a mastic mass appearing in Figure 2 as the layer 38 which, as indicated in Figure 2, may be tapered with a maximum thickness at the middle of the strip, but which extends the entire width of the strip. This mastic is made up of the usual matrix of asphaltum to which has been added, in a uniform and homogeneous mixture, fine flakes of mica 40. The maximum size of these flakes is the size that will pass through a forty mesh screen, but, for best results, I prefer to have the greater proportion of these flakes of a size to pass through a sixty mesh screen. After receiving the layer 38 in the applicator 18, the strip receives a layer of asphaltum 42 over its central portion only, extending from the point 44 to the point 46 of Figure 2. And in the applicator 20 it receives the relatively thin backing coat 48 of asphaltum.

The thickness of the layer 42 is just sufficient to provide an embedding matrix for the grits 24 without having the grits thrust in among the mica flakes 40.

30 The subsequent application of grits by the hopper 22 may be only over the central portion of the strip from point 44 to 46 or not. In either instance, substantially the product of Figure 2 will result because the layer 38 will be so much cooler than the fresh central surface carrying the layer 42 that the pressure of the roller 26 may be adjusted to secure retention of grits 24 by the layer 42 but not by the layer 38.

Referring now to Figure 4 I have illustrated 40 a modification in which the layer 42 has been omitted and the grits are pressed directly into the layer 38. This embodiment, when the percentage of mica in the layer 38 is low and the mica flakes small, will retain the grits satisfactorily.

I am aware of prior art shingles in which a large percentage of large mica flakes are placed in a layer of asphaltum next the felt base 10, and I have shown a diagram of that construction in 50 Figure 3 for purposes of comparison and explanation. With the relatively large amount of relatively large flakes indicated in Figure 3, it is necessary to employ a top layer 50 of asphaltum without mica, of materially greater thickness than the layer 42 of Figure 5. This is because

the rigidity of the mica bearing layer 52 of Figure 3 is so high that any slight contact between the grits 24 and the layer 52 would create an irregularity that would soon develop a hole under exposure to the weather. I also find that, compared with the present invention, shingles according to Figure 3 are more rigid, and there is a definite tendency under prolonged exposure to the weather for the layer 52 to cleave away from the base 10 or from the cover layer 50 or both.

According to my invention, the mica flakes 40 are not only of the relatively much smaller size previously specified and of maximum dimensions not greater than the dimensions of one of the grits 24, but the percentage of mica by weight in the layer 38 is preferably from 6% to 8% with a maximum not exceeding 10%. This decreased percentage of mica leaves the layer 38 sufficiently plastic and sufficiently bonded to the base 10 and cover layer 42 to eliminate any tendency in the shingle to split into laminations.

With respect to thermal-conductivity, it is noted that at the surface of contact between any two dissimilar substances, there is a barrier to heat flow incident to the physical structure of the contact surface, and this barrier is in addition to the resistance of each of the substances themselves to the transmission of heat. In each of the embodiments of Figure 3 and Figure 5, we can, therefore, consider a possible path of heat flow through the asphaltum. This path will be tortuous because it has to detour each individual flake of mica, and its total length will be materially in excess of the thickness of the layer 38 or 52 by approximately the same amount in both embodiments. Considering the other path of heat flow in a geometrically straight line, the path through the layer 38 will necessarily penetrate a materially smaller thickness of mica than in the layer 52 because the layer 52 contains a much larger percentage of mica. But in the layer 38 the direct path may be subject to two or three times as many surface barriers as in the layer of Figure 3. Accordingly, it is evident that a given weight of mica will impose a much greater obstacle to heat flow when it is present in the smaller flakes of Figure 5 than when it is present in the large flakes of Figure 3. Accordingly, the mica is more effectively utilized for insulating purposes in Figure 5 than in Figure 3.

The finished strip may be slit along the line x-x (Figure 2) to make roll roofing, or the strips resulting from such slitting may be cut transversely to form either individual or strip shingles.

The foregoing procedure appears to be applicable with mica flakes up to a fineness of about 80 mesh or 100 mesh. But mica in much finer flakes than these can be used, even down to mica flour. Especially with such very fine flakes, the procedures of Figures 6 and 8 are advantageous to insure that the bulk of the flakes will be positioned substantially parallel to the sheet as a whole, in which position they constitute a more effective thermal insulation barrier than if they were arranged at random in the asphaltic mass. Referring first to Figure 6, I have illustrated the same looper 16 as in Figure 1a. From the looper the strip passes under the mixed 54 which deposits the previously mixed mica and asphalt on the moving strip in substantially the quantity desired, but only approximately in the desired shape. Thereafter the strip is drawn under a series of combs indicated by the reference character 56. Each comb comprises a tube 58

through which superheated steam or the products of gaseous combustion may be passed to keep the comb at such a temperature that the asphalt will not stick to it. Projecting downwardly and forwardly from the side of each tube is a plurality of teeth 60 having fine needle-like points. Figure 7 indicates how the points score fine lines in the asphaltic mass as the sheet 10 passes under them. Preferably, the point on successive combs are staggered or offset so that a kneading will take place in the asphaltic mass accompanied by slight longitudinal displacement that will generate sufficient flow to turn most of the mica flakes parallel to the direction of motion of the strip. In this way, even with extremely minute flakes, a fair degree of parallel alignment, similar to that illustrated in Figures 4 and 5 can be secured. At 62 I have indicated a protecting hood over the comb, so that the air space inside the hood may become fairly well heated and assist the natural thermal conduction of heat down the individual comb teeth 60 in keeping the points of the teeth hot enough not to pick up asphalt.

Referring now to Figure 8, the same looper 16 delivers the strip to a series of applicator units of which three have been illustrated. Each applicator comprises a trough 64 containing asphalt heated considerably hotter than its melting temperature so that it is freely fluid. The heated dipping roll 64 is partly immersed in the asphalt and transfers a film to the heated transfer roll 66 which transfers a film to the heated applicator roll 68. The applicator roll rides directly on the strip 10. The strip 10 is preferably pressed lightly against the applicator roll by a bottom roll 70 forced up against it by a coil spring 72. I prefer to drive the applicator roll 68 at a speed approximately 10% slower than the speed of the strip 10 so that there will be a slight wiping or painting action, as the relatively cool strip receives from the roll most of the film of asphalt carried thereby. Each of the asphalt applicators is preferably housed in a hood 74 so that the air around the rolls 64, 66, and 68 will be only slightly cooler than the rolls themselves and will not cool the film appreciably. After passing through the first applicator, the strip receives a very thin surface of the fine mica grits from the hopper 18. The amount of mica that can be applied in this way on one application is limited because the coating of mica must not be thick enough to develop any plane of cleavage in the finished product.

Thus the strip passes under such applicators and receives alternate thin layers of asphaltum and mica, and the wiping or painting action of each applicator roll 68 forces the additional asphalt into the mica sufficiently to get a firm bond with the previous layer of asphalt. After passing the last applicator, the strip may receive a final top coating of asphalt from the delivery pipe 78, which top coating may be materially thicker than the previous paint coatings, and may be formed with a taper as clearly indicated at 80 in Figure 9 as by shaping it as in Figure 1.

Figure 9 illustrates such a product as is delivered by the apparatus diagrammed in Figure 8. It will be noted that the strip 10 carries a substantially homogeneous mass of asphalt on its upper surface in which there are three layers at 82, 84, and 86 where there is a percentage of mica. At the center of each of these layers, the mica concentration may run as high as 30% without impairing the bond between the different

layers of asphalt, but of course when averaged throughout the entire mass, the percentage will be much smaller. However, the mica that is used is so disposed as to be of maximum effectiveness in contributing to the insulating character of the finished product.

Without further elaboration, the foregoing will so fully explain my invention that others may, by applying knowledge current at the time of application, readily adapt the same for use under various conditions of service. It will, for instance, be obvious, that when it is not desired to secure an unusually thin layer of asphalt at each application, in building up the strip as in Figure 9, the asphalt can be simply poured onto the strip in the usual way.

I claim:

1. The method of making roofing which comprises: moving a strip longitudinally; superimposing on said strip a mastic material having fine mica flakes homogeneously mixed therein; combing said mastic material with a plurality of rows of heated stationary points into the approximate cross-sectional configuration of the finished product; and smoothing the surface of the combed material into the exact configuration of the finished product.

2. The method of making roofing which comprises: moving a strip longitudinally; superimposing on said strip a mastic material having fine mica flakes homogeneously mixed therein; aligning said flakes approximately with the plane of the strip by combing said mastic material with a plurality of rows of heated stationary points; and smoothing the surface of the combed material into the exact configuration of the finished product.

3. The method of making roofing which comprises: moving a strip longitudinally; superimposing on said strip a mastic material having fine mica flakes mixed therein; combing said mastic material with a plurality of rows of heated stationary points; and smoothing the surface of the combed material.

4. The method of preparing roofing which comprises moving a strip longitudinally; applying a hot coating to said strip; permitting said hot coating to cool at least partially; applying a second hot coating over a portion only of the area of said strip; and depositing grits on said strip at a time when said second coating is still hot enough to receive and retain said grits, but said first coating is too cool to retain said grits.

JOHN LOGAN, JR.
